UNITED STATES PATENT OFFICE.

WILLIAM HART, OF NEW BEDFORD, ILLINOIS.

STACKER FOR THRESHING-MACHINES.

SPECIFICATION forming part of Letters Patent No. 590,886, dated September 28, 1897.

Application filed February 10, 1897. Serial No. 622,744. (No model.)

To all whom it may concern:

Be it known that I, WILLIAM HART, of New Bedford, in the county of Bureau and State of Illinois, have invented a new and Improved 5 Stacker for Threshing-Machines, of which the following is a full, clear, and exact description.

The object of the invention is to provide a new and improved stacker for threshing-machines which is simple and durable in construction and arranged to be conveniently folded while transporting the machine from place to place and adapted to be turned in any desired direction when in use to discharge 15 the straw to any desired point.

The invention consists of certain parts and details and combinations of the same, as will be fully described hereinafter and then pointed out in the claims.

Reference is to be had to the accompanying drawings, forming a part of this specification, in which similar characters of reference indicate corresponding parts in both views.

Figure 1 is a side elevation of the improvement as applied, and Fig. 2 is a plan view of the same with parts broken out.

On the rear end of the lower sill A' of the separator-frame A is secured an auxiliary frame B, carrying a vertically-disposed pivot 30 C, on which is mounted to turn the turn-table D, provided with suitable bearings for a transversely-extending shaft E, connected by well-known suitable means with a part of the threshing-machine, so that the shaft E is rotated when the threshing-machine is set in motion. On the shaft E is hung the lower section F' of the apron-frame F, provided with an upper section F², pivotally connected at F³ with the upper end of the lower section 35 F'. The upper section F² when in use is swung into such a position as to be in alinement with the lower section F', as shown in the drawings, or folded upon the under side thereof (see dotted lines, Fig. 1) when the device 40 is not in use and the machine is transported from one place to another. Suitable hooks F⁴ and eyes F⁵ are then used to hold the sections together.

On the shaft E and within the section F' of the apron-frame is secured a pulley G, over which passes the apron or slat belt H, also passing over a series of rollers G', journaled

in the sides of the sections F' and F², to finally pass over the pulley G², held in the outer end of the section F². The apron or slat belt H 55 is preferably provided on its outer face with transverse slats H', each containing a row of outwardly-projecting pins H² to securely hold the straw and chaff in place on the belt, while the latter has a traveling motion and carries 60 the material from the machine to the stack, it being understood that the material is discharged upon the stack from the apron or slat belt H at the pulley G².

The section F' is adapted to be temporarily 65 locked when in an inclined position to the turn-table D to permit of swinging the section F into an extended position or into folding position. For this purpose I provide braces I, hinged on the sides of the section 70 F' and adapted to engage staples I' on the sides of the turn-table D. Now in order to give the desired position to the section F² relative to the section F' I provide the following device: In the outer end of the turn-table D is journaled a transversely-extending drum J, having a suitable handle J', adapted to be taken hold of by the operator for turning the drum to wind up or unwind thereon, the ropes K extending on the sides of the 80 stacker, as indicated in the drawings. Each of the ropes K extends from the drum or windlass J over pulley L, journaled in the corresponding side of the section F', near the upper end thereof. The rope thence extends 85 inwardly and passes over a pulley N', journaled in the corresponding outer end of a transversely-extending equalization-beam N, provided at its middle with a ring or staple N², hung on an arm or equivalent holder O, 90 attached to the upper sill A² of the separator-frame A, the said support slightly projecting rearwardly beyond the sill, as shown in the drawings. The ropes K after leaving the pulley N' extend outwardly and are rigidly fastened at L² to the corresponding sides of the section F², near the outer end thereof and near the bottom of the same, as plainly indicated in Fig. 1. A pulley L' is arranged near the inner end of the section F to be engaged by 95 the corresponding rope K when the section F² is to be folded. Now it will be seen that when the several parts are in the position shown in Fig. 1 and the operator turns the 100

drum J so as to wind up the two ropes K simultaneously a pull is exerted in an upward direction on the section F², so as to swing the same and the section F' upwardly, according to the increase in the height of the stack formed. The material is now discharged at the pulley G² at a higher elevation.

When it is desired to discharge the material to a lower point, the operator turns the drum J in a reverse direction, so as to unwind the ropes K simultaneously and to permit the sections F' F² to swing downward by their own weight until the desired point is reached for the material to be discharged at the pulley G².

When it is desired to fold the section F² onto the under side of the section F', as previously mentioned, the section F' is brought in such a position that the braces I can be engaged with the staples I'. When this has been done, the windlass J is turned to unwind the ropes K to permit the section F² to swing downward from the hinge F³ on the now fixed outer end of the section F'. During the downward-swinging motion of the section F² the ropes K engage the pulleys L', previously mentioned. The section F², when a vertical position is reached, is swung upward and inward by hand against the under side of the section F' and fastened thereto by the hooks and eyes F⁴ and F⁵. The braces I are now disconnected from the staples I' and connected with staples I² and the section F' is permitted to swing by its own weight downward on a further turning of the windlass to unwind the ropes K. When the stacker-sections F' F² are to be extended, the windlass is turned to wind up the ropes K to swing section F' upward to permit of connecting the braces I with the staples I'. The section F² is now unhooked from section F' and permitted to swing downward into an approximately vertical position. The operator now actuates the windlass to wind up the ropes K. As the latter pass over the pulleys L' an upward pull is exerted on the section F² to swing the same into alignment with the section F', as shown. The braces I are then again disconnected to permit of swinging the extended sections up or down, according to the height of the stack. By having the transverse beam N hung on the support O the said beam is free to swing in any desired direction, so that when the turn-table D is turned on the pivot C the said beam N assumes a corresponding position to the stacker-frame F and the section F² can be swung up or down by winding up or unwinding the ropes K on the drum J, as before explained.

60 The several pulleys L L' L' and N' N' are

specifically described as pulleys, but, as will be readily understood, they are generically guides, and any equivalent guide may be employed in practice.

Having thus fully described my invention, 65 I claim as new and desire to secure by Letters Patent—

1. A stacker, comprising a turn-table, an apron-shaft journaled on the said turn-table, an apron-frame hung on the said shaft and made in two sections hinged together, one section being adapted to be held in an inclined fixed position relative to the turn-table, an equalization-beam hung on a support attached to the separator-frame, a windlass 75 journaled on the turn-table, and ropes connected with the said windlass and the outermost section of the apron-frame, the said ropes passing over pulleys held on the said sections and on the said equalization-beam, 80 substantially as shown and described.

2. The combination of a turn-table, an apron-frame hung on the turn-table so as to swing vertically, the apron-frame comprising inner and outer sections having a hinge connection, ropes at the sides of the apron-frame for raising and lowering the frame-sections, an equalizing-bar supported above the apron-frame, pulleys on the equalizing-bar, pulleys on the inner section of the apron-frame, pulleys on the outer section of the apron-frame adjacent to the inner end and means for winding the ropes, said ropes being connected with the said outer section and passing over the pulleys on the equalizing-bar, and over the 95 pulleys on the said inner frame-section, the pulleys on the said outer section serving to engage and guide the adjacent runs of the ropes when the said outer frame-section is being raised and lowered, substantially as described.

3. In a stacker, the combination of an apron-frame, comprising two sections having hinged connection, the outer section being adapted to be lowered from a position in line with the inner section, ropes connected with the outer section and capable of raising the same, overhead guides, above the apron-frame for guiding the ropes, guides located on the inner section of the apron-frame and over which the ropes also pass, and additional guides for the ropes, said additional guides being located at the inner end of the outer section and serving to engage the ropes when the outer section is being lowered.

WILLIAM HART.
